[57] CLAIM

The ornamental design for an electrical can opener with automatic stop, substantially as shown and described.

DESCRIPTION

FIG. 1 is a left side elevational view of an electrical can opener with automatic stop showing my new design;

FIG. 2 is a front elevational view thereof;

FIG. 3 is a rear elevational view with the cutter removed thereof;

FIG. 4 is a rear elevational view thereof;

FIG. 5 is a right-side elevational view thereof;

FIG. 6 is a right-side elevational view showing the cutter in an alternative position to that as shown in FIG. 5 thereof;

FIG. 7 is a top plan view thereof;

FIG. 8 is a bottom plan view thereof;

FIG. 9 is a sectional view thereof.

FIG.1.

FIG.2.

FIG. 3.

FIG. 4.

FIG. 5.

FIG. 6.

FIG.7.

FIG.9.

FIG.8.
